UNITED STATES PATENT OFFICE

2,120,780

FAN

Walter A. Geise, Flint, Mich., assignor to General
Motors Corporation, Detroit, Mich., a corpora-
tion of Delaware

Application January 20, 1934, Serial No. 707,493

3 Claims. (Cl. 170—159)

I have found that the noise which is produced as the result of the operation of the propelling engine of an automotive vehicle may be considerably reduced or, at least, rendered much less apparent or objectionable by so constructing and/or arranging the blades of the engine cooling fan that one of them imparts to the air an impulse whose characteristics differ from that imparted to the air by another blade or, to be more specific, by making the angular pitch and/or the size and/or the shape of one of the blades different from that of another blade.

My invention may be embodied in multi-blade fans which have even or uneven numbers of blades; and in either type of fan, the angular pitch and/or the size and/or the shape of one blade may be different from the angular pitch and/or the size and/or the shape of the other blade or blades or the angular pitch and/or the size and/or the shape of one blade may be different from the angular pitch and/or the size and/or the shape of another blade or blades but the same as the angular pitch and/or the size and/or the shape of still another blade or blades.

For a better understanding of the nature and objects of the present invention, reference is made to the following specification in which there are described the preferred embodiments of my invention which are illustrated in the accompanying drawing, in which:

Figure 1 is a fragmentary side elevation of the front end of an automotive vehicle in which is installed an engine cooling fan in which is embodied my invention.

Figure 2 is a front elevation of the engine cooling fan which is shown in Figure 1.

In Figure 3, A—A, B—B, C—C and D—D indicate, respectively, sections on the lines A—A, B—B, C—C and D—D of Figure 2.

Figures 4 and 5 are, respectively, a side elevation and a front elevation of another engine cooling fan in which my invention is embodied.

In the drawing, the reference character 9 indicates the water cooling radiator of an automotive vehicle and the reference character 10 the propelling engine thereof. To draw cooling air through the radiator and force it over the engine, there is provided a fan 11 which is arranged to be driven through any ordinary or suitable mechanism by the engine 10.

The fan 11, which is shown in Figures 1, 2 and 3, consists of a hub 12 on which there are mounted equi-angularly around the axis of rotation of the fan four propeller or screw type fan blades 13, 14, 15 and 16 which may be of the

same size and shape or of different sizes and/or shapes but, as Figure 3 clearly shows, have different angular pitches. The fan 11, which is shown in Figures 4 and 5, consists of a hub 18 to which there is secured a spider 19 on which there are mounted equi-angularly around the axis of rotation of the fan four propeller or screw type fan blades 20, 21, 22 and 23 which may have the same or different angular pitches but are, as Figure 5 clearly shows, of different sizes and/or shapes.

What angular pitches and/or sizes and/or shapes the several blades of a fan in which my invention is embodied should be given to produce a fan which gives the most highly satisfactory results may be determined by experiment. However, it should here be noted that the fan which will operate most satisfactorily in one installation is not necessarily the fan which will operate most satisfactorily in another installation and, consequently, that since, practically speaking, what is to be considered is not how quietly the fan operates when divorced from its intended surroundings, but how quietly the installation as a whole is when the fan is operating, the experiments should be conducted with the fan incorporated in the installation in which it is intended to be used and the most highly satisfactory results should be considered to have been attained when the installation as a whole is most quiet when the fan is operating.

To eliminate the possibility of a misunderstanding of what has been said in the next preceding paragraph, I should, perhaps, point out that it is not necessary by experiment to design a fan for each example of an installation, since when a fan suitable for a particular example of an installation has been produced, similar fans may, without further experimentation, be satisfactorily employed in all examples of that installation.

Although I have shown and described as preferred embodiments of my invention four-blade fans, it will be understood that the principles underlying my invention may be incorporated in fans which have a greater number of blades as well as in two-blade and three-blade fans.

I claim:

1. A screw propeller which consists of more than three substantially identical blades of which each differs in pitch and is spaced angularly around the axis of rotation of the propeller from each of the others, so disposed that they rotate in substantially the same plane and are arranged around the axis of rotation of the pro-

steller in numerical order with respect to the values of their pitches.

- 5 2. A screw propeller which includes at least three blades which are substantially identical except that each differs from each of the others in pitch, are so disposed that they rotate in substantially the same plane and are arranged around the axis of rotation of the propeller in the numerical order of their pitches.
- 10 3. In an automotive vehicle in which there is included a liquid cooled internal combustion propelling engine, and a radiator for cooling the engine cooling liquid located near the engine, a

screw propeller which consists of a plurality of substantially identical blades, so disposed that they rotate in a single plane positioned between said radiator and engine whereby air is drawn through the former and propelled over the latter, each of the blades differing in angular pitch from each of the others and spaced angularly around the axis of rotation of the propeller in the numerical order of their pitches, so that in the operation of the propeller the noise produced as the result of the operation of the engine is minimized.

WALTER A. GEISE.
